SHOCKPROOF ELECTROMAGNET

Theodore M. Spangler, Schenectady, N. Y., assignor
to General Electric Company, a corporation of
New York

Application August 22, 1944, Serial No. 550,523

8 Claims. (CL 175—336)

My invention relates to electromagnets, more particularly to electromagnets whose armatures are normally in their unattracted positions, and has for its object simple and reliable means for mounting the armature so that it is free from the effects of severe shocks.

My invention is especially applicable to pivoted armatures. A pivoted armature may be balanced about its pivot so as to be substantially free from forces set up by shocks caused by the inertia of the armature. However, ordinarily the armature in its unattracted position is brought to rest by a biasing spring against a solid or stationary stop. In the event of a shock, this stop transmits the shock to the armature whereby the armature is thrown toward its attracted position.

In carrying out my invention in one form, I provide stop means for the armature biasing spring together with a relatively weak spring for holding the armature against this stop means when the armature is in its unattracted position. In a preferred form I provide a spring strip extending lengthwise of the armature and having one end secured to one end of the armature. The other end of the spring strip is provided with a cross member which projects beyond opposite sides of the armature, and when the armature is in its unattracted position, this cross member rests on two stops on opposite sides of the armature. A biasing spring for biasing the armature to its unattracted position bears on this strip at a point adjacent the cross member so that when the armature is in its unattracted position, the force of the spring is applied largely to the stops. However, if the armature tends to move still farther in the direction toward its unattracted position in response to a shock, the spring strip bends to provide for this movement.

For a more complete understanding of my invention, reference should be had to the accompanying drawing, Fig. 1 of which is a side elevation view of an overload relay provided with an electromagnet embodying my invention; Fig. 2 is a front elevation view of the device of Fig. 1; Fig. 3 is a sectional view taken along the line 3—3 of Fig. 1 looking in the direction of the arrows, while Fig. 4 is a fragmentary view showing a modified form of my invention.

I have shown my invention in one form as applied to the pivoted armature 1 of a current responsive overload relay having a current coil 2 which is connected in the circuit, such as a motor circuit or the plate circuit of a radio transmitter, to be protected and a resetting coil 3 provided with an armature 4.

Upon the occurrence of a predetermined over-load current in the coil 2, the armature 1 is moved counterclockwise about its central supporting pivot 5 to an attracted position whereby its lower end engages a latch 6 for the armature 4, moving the latch clockwise about its pivot 7 against the force of a biasing spring 8 to release the armature. The armature 4 is thereupon pulled by its biasing spring 9 downward clockwise about its pivot 10 to its unattracted position, the coil 3 being deenergized. This movement of the armature 4 correspondingly moves an arm 11 secured to it and carrying a bridging contact 12. The arm 11 moves clockwise about the pivot 10 and moves the bridging member 12 toward the right hand to disengage the two stationary contacts 13 and 14 whereby the magnet 2 is deenergized.

Preferably the switch represented by the bridging member 12 and its stationary contacts 13 and 14 is connected in the circuit so as to control the current passing through coil 2 and the device to be protected. Thus, when the bridging member 12 is moved to its open circuit position, the coil 2 is deenergized and the armature 1 is moved by its biasing spring 15 to its unattracted position, as shown in the drawing. To provide for continued operation, the device is reset by energizing momentarily the coil 3 by means of a suitable manually operated switch (not shown) such as a push button switch, whereby the armature 4 is moved to its attracted position and secured in that position by the latch 6. The parts are then as shown in the drawing, the armature 1 being normally in its unattracted position and moved only momentarily to its attracted position upon the occurrence of an overload. After the armature 4 has been reset, the coil 3 is deenergized.

In accordance with my invention, I provide a resilient stop means for the armature 1 for limiting its movement to its unattracted position. This stop means comprises a spring strip 16 extending lengthwise in substantially parallel relation with the armature 1 and having its upper end 17, as seen in the drawing, rigidly secured to the upper end of the armature as by brazing or welding. This strip extends downward along the armature 1 on the side of the armature remote from the coil 2 to a point below the pivot 5 where the strip 16 is provided with a transversely extending portion or cross member 18 (Fig. 2). This cross member 18 may be formed integrally with the strip. Its length is greater than the width of the armature 1 so that at each end it extends beyond the corresponding side or edge of the

armature, as seen clearly in Fig. 2. For increased strength, the lower end or edge of the cross portion 18 is bent at right angles toward the armature providing a flange or rib 19.

This rib 19 at its opposite ends rests on stationary stops 20 and 21 on opposite sides of the armature when the armature is in its unattracted position, as shown in the drawing, the rib 19 being held against the stops by the compression biasing spring 15. One end of the spring 15 is seated in a depression 22 in the strip 16 adjacent its lower end while the other end of the spring is seated on an adjustable supporting member 23, this point of engagement 22 of the spring 15 with the strip being below the pivot 5. The armature 1 is thereby biased by the spring 15 to its unattracted position. Preferably, the spring strip 16 is bent or shaped and secured to the upper end of the armature 1 in such a manner that the rib 19 is biased against the adjacent side of the armature by reason of the spring force exerted by the strip itself. Thus, when the armature is in its unattracted position, the force of the strip 16 biases the armature counterclockwise about the pivot 5, i. e. toward its attracted position, into engagement with the rib 19. The rib 19, as previously stated, is held against the supports 20 and 21 by the relatively strong biasing spring 15.

Thus it will be observed that, with the armature as shown in its unattracted position, it is biased by the relatively weak spring 16 against a spring pressed stop which is the flange or rib 19, the bias against this stop being, however, counterclockwise about the pivot 5, i. e., the direction that the armature moves when attracted by the coil 2. In a clockwise direction, the armature has a limited freedom of movement against this counterclockwise biasing spring force applied by the spring strip 16. Thus a shock or component of a shock in a direction from the left hand to the right hand, as seen in Fig. 1, is applied by the supporting parts to the pivot 5 and from the pivot 5 to the armature 1. However, since the armature is balanced about the pivot, this shock force does not tend to cause rotation of the armature. Any rebound of the flange 19 from the supports 20 and 21 from such a shock is transmitted to the armature only through the spring strip 16 which absorbs the shock so that no appreciable rotation of the armature is produced.

Shock forces in the opposite direction, i. e., from the right hand toward the left hand, are applied not only to the pivot 5 and to the armature but are applied through the spring 15 and the flange 19 to the armature. While the shock may be transmitted by the spring 15 to the flange with sufficient intensity to throw the lower end of the armature away from the flange, i. e., cause clockwise rotation of the armature, this rotation is in the direction opposite to that required to trip the latch 6, and therefore may be neglected. Actually, however, the spring 15 serves to absorb the transmission of shock to the flange 19 so that very little clockwise rotation of the armature 1 is caused by a severe shock.

In the modified form of my invention shown in Fig. 4, I provide a supporting rod 24 on which the two helical biasing springs 25 and 26 are mounted. This rod extends loosely through a hole in the armature and at its right-hand end extends loosely through a hole in the supporting bracket 27. It is provided on its right-hand end with a suitable washer and nut, as shown, forming a flange. The spring 26 bears at its right end

on the bracket 27 and at its left hand on a flange 28 rigidly secured to the rod 24. The spring 26, which is relatively weak as compared with the spring 25, has its left end seated against a flange 29 on the left-hand end of the rod, and its right end bearing against the adjacent side of the armature 30, thereby to hold the armature resiliently against the flange 28.

It will be understood that the magnet coil and other parts shown in Fig. 1, with the exception of the springs 15 and 16 and the stops 20 and 21, are associated with the armature 30 in the manner disclosed in Fig. 1 with respect to the armature 1. With the armature 30 in its unattracted position as shown in Fig. 4, the spring 26 holds the rod 24 in its lefthand extreme position, as shown, while the weaker spring 25 biases the armature in a counterclockwise direction about its pivot and thereby holds the lower end of the armature against the stop 28 on the rod 24. It will be observed that the force of the spring 25 is applied in a direction opposite to the force applied by the spring 26.

With the arrangement of Fig. 4, when the coil is energized, the armature is moved counterclockwise against the force of the spring 26, the rod 24 sliding toward the right hand through the loose hole for it in the bracket 27. It will be observed that a shock from the left hand toward the right hand applied to the support is transmitted through the rod 24 and the spring 25 to the armature, but the force of the shock thus transmitted is absorbed to a very great extent by the spring 25 so that the shock does not produce any appreciable counterclockwise rotation of the armature.

It will be understood that, in the modified form of Fig. 4, the spring 26 corresponds with the spring 15 of Figs. 1-3 inclusive. In both forms, a definite stop means is provided for this strong spring while the armature is biased by a weaker spring 16 or 25 in a direction toward its attracted position against this stop means. Thus, in Figs. 1-3 inclusive, the spring 15 is provided with stop means comprising the flange 19 and the supports 20 and 21, while the armature is biased by the spring 16 against the flange 19.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. A shockproof electromagnet comprising a support, a coil on said support, an armature pivotally mounted on said support for movement between attracted and unattracted positions, a relatively strong first spring on said support for biasing said armature to said unattracted position, stop means for said first spring for limiting the movement of said armature by said first spring, and a relatively weak second spring arranged when said armature is in said unattracted position to apply a force to said armature in a direction opposite to the force applied by said first spring, said second spring yielding to prevent the transmission of a shock from said support to said armature in a direction to turn said armature on its pivot toward said attracted position.

2. A shockproof electromagnet comprising a support, a coil on said support, an armature pivotally mounted on said support for movement be-

tween attracted and unattracted positions, a relatively strong first spring on said support for biasing said armature to said unattracted position, stop means on said support for said first spring for limiting the movement of said armature by said first spring, a relatively weak second spring cooperating with said support arranged when said armature is in said unattracted position to apply a force to said armature tending to move said armature toward its attracted position thereby to hold said armature against said stop means, said second spring yielding to prevent the transmission of a shock from said support to said armature in a direction to turn said armature on its pivot toward said attracted position.

3. A shockproof electromagnet comprising a support, a coil on said support, an armature pivotally mounted on said support for movement between attracted and unattracted positions, a relatively strong first spring on said support for biasing said armature to said unattracted position, stop means for said first spring for limiting the movement of said armature by said first spring while providing for additional movement of said armature beyond said unattracted position, and a relatively weak spring carried by said armature for biasing said armature toward said attracted position against said stop means when said armature is in its unattracted position.

4. A shockproof electromagnet comprising a support, a coil on said support, an armature pivotally mounted on said support for movement between attracted and unattracted positions, a relatively strong first spring, a member movable by said first spring against said armature thereby to bias said armature to its unattracted position, a stop on said support for said member for limiting the movement of said armature by said first spring, and a relatively weak spring for biasing said armature in an attracted direction against said member.

5. A shock proof electromagnet comprising a coil, an armature for said coil pivotally mounted for movement between attracted and unattracted positions, a spring strip having one end secured to one end of said armature and extending lengthwise of said armature, a stop engaged by the other end of said strip when said armature is in its unattracted position, and a spring engaging said strip adjacent said other end for biasing said strip against said stop and said armature in its unattracted position, said armature when moving to its attracted position engaging said end thereby to move said end away from said stop against the force applied by said biasing spring.

6. A shockproof electromagnet comprising a coil, an armature for said coil pivotally mounted

intermediate its ends for movement of a first end to an attracted position with relation to said coil, a spring member having one end secured to said first end of said armature and extending along said armature to the other side of the pivot of said armature, a cross member on said spring strip having its ends projecting beyond opposite sides of said armature, stationary stop members on opposite sides of said armature, and a spring for biasing said armature to an unattracted position bearing on said spring strip at a point between the pivot of said armature and said cross member thereby to bias said armature to an unattracted position with said cross member in engagement with said stops, said armature in moving to its attracted position engaging said cross member and moving said cross member against the force applied by said spring.

7. A shockproof electromagnet comprising a support, a coil on said support, an armature pivotally mounted on said support for movement between attracted and unattracted positions, a member extending transversely with respect to said armature on one side of said pivot, a projection secured to said member intermediate its ends, a relatively strong spring on said member bearing on said support and said projection thereby to bias said member to a predetermined position on said support and said armature to said unattracted position, and a relatively weak spring on said member bearing on said armature thereby to hold said armature against said projection, said armature when moving on its pivot to its attracted position upon energization of said coil moving said member against the force applied by said relatively strong spring.

8. A shockproof electromagnet comprising a support, a coil on said support, an armature pivotally mounted on said support for movement between attracted and unattracted positions, said armature being provided with an aperture on one side of said pivot, a rod extending loosely through said aperture and having one end extending loosely through an aperture in said support, a first flange on said end of said rod, a second flange secured to said rod intermediate its ends, a relatively strong spring surrounding said rod bearing on said support and said second flange thereby to bias said rod to a position with said first flange in engagement with said support, a third flange on the other end of said rod, and a relatively weak spring on said rod bearing on said third flange and said armature thereby to hold said armature against said second flange, said armature when moving on its pivot to its attracted position upon energization of said coil moving said rod against the force applied by said relatively strong spring.

THEODORE M. SPITTLER.
